(57) **CLAIM**

The ornamental design for a hand tool, as shown and described.

DESCRIPTION

FIG. 1 is a perspective view of a hand tool showing the new design.

FIG. 2 is a right side elevation view thereof.

FIG. 3 is a rear elevation view thereof.

FIG. 4 is a bottom plan view thereof.

FIG. 5 is a top plan view thereof.

FIG. 6 is a left side elevation view thereof.

FIG. 7 is a front elevation view thereof.

FIG. 8 is a perspective view of the main component of the hand tool.

FIG. 9 is a right side elevation view thereof.

FIG. 10 is a rear elevation view thereof.

FIG. 11 is a bottom plan view thereof.

FIG. 12 is a top plan view thereof.

FIG. 13 is a left side elevation view thereof; and,

FIG. 14 is a front elevation view thereof.

The broken line showing of the cable is provided for purposes of environment and forms no part of the claimed design.
